UNITED STATES PATENT OFFICE.

RALPH W. WILSON, OF NEW YORK, N. Y., ASSIGNOR TO THEODORE W. FOSTER & BRO. COMPANY, OF PROVIDENCE, RHODE ISLAND, A CORPORATION OF MAINE.

TOILET BOX.

Application filed August 29, 1923. Serial No. 659,856.

My invention relates to a toilet or vanity box and my object is to provide one which is of a construction which shall be quite compact and have a desirably thin shape. Other advantages will appear from the following description:

Fig. 1 represents a preferred form in perspective;

Fig. 2, a central section;

Fig. 3, a side elevation;

Fig. 4, a detail;

Fig. 5, represents a modification in perspective;

Fig. 6, a central section of the same;

Fig. 7, a side elevation.

I provide two halves, 1 and 2, each of which is of a general saucer shape, which may be pivoted together, as indicated at 3, so that their edges substantially meet like the halves of a clam-shell, as indicated in Figs. 2 and 3. The box contains one or more compacts, such as a face powder compact 4, and a rouge compact 5, held therein in a suitable way. It also contains one or more mirrors. In Fig. 2, I have shown two mirrors 6 and 7, which, if desired, may be carried upon a thin plate 8, suitably pivoted as on the common pivot 3, and which, if desired, may be of such a size that it lies between the meeting edges, as indicated in Fig. 2. This plate may carry a suitable push-catch 9, which will engage the two halves, such as by engaging over the in-turned edges thereof, as indicated at 10—10. When closed and latched, the device is quite compact.

One or both of these compacts, such as the one illustrated by 4, may be moulded into a saucer-shaped metallic container 11, thereby providing a shape which closely fits the interiorly concave shape of the half 1 and may be held therein, if desired, by a flexible metallic portion 12, which may be snapped or sprung into the half portion by engagement under the inturned edge 10, as shown. Either half of the box may be opened with ease by pressing upon the catch 9 and with the thumb nail inserted in the slight angle formed at 17 Fig. 3 between the inturned edge of the half and the catch or plate 8.

Figs. 5 to 7 inclusive show a slight variation in which the mirror 13 is held by a part 14, in a manner similar to that in which the compacts of the other figures are held.

By this construction, a quite compact box 55 is provided, and which is of neat, attractive appearance. 15 and 16 represent powder puffs, which may be provided if desired.

I am aware that various modifications of my invention may be made without departing from its scope.

What I claim as new is:

1. A toilet box comprising two saucer-shaped covers and a partition hingedly connected together, and means for securing both 65 of said cover members to the partition, said securing means comprising means projecting from opposite sides of said partition for engagement with the covers.

2. A toilet box comprising two saucer-shaped members, a hinge for pivotally securing said members together, a partition hingedly mounted between said members and adapted when the members are closed to form two closed compartments, and 70 means upon opposite sides of said partition and adapted for engagement with the saucer-shaped members whereby either of the saucer-shaped members may be secured to the partition to form a closed compartment 75 when the other member is open.

3. A toilet box comprising a plurality of cover members and a partition, means for pivotally connecting said cover members and said partition together with the partition interposed between the cover members, an inwardly turned flange defining the edge of each of the cover members and forming a seat for said partition, and means carried by said partition and adapted for engagement with the inwardly turned flanges of the cover members for securing said cover members in closed position with respect to said partition.

Signed at New York city this 21st day of 85 August, 1923.

RALPH W. WILSON.
